UNITED STATES PATENT OFFICE.

CARL J. E. WAXBOM, OF WESTERVILLE, OHIO, ASSIGNOR TO THE JEFFREY MANUFACTURING COMPANY, OF COLUMBUS, OHIO, A CORPORATION OF OHIO.

MINING APPARATUS.

1,276,141.

Specification of Letters Patent. Patented Aug. 20, 1918.

Application filed October 11, 1912. Serial No. 725,323.

To all whom it may concern:

Be it known that I, CARL J. E. WAXBOM, a citizen of the United States, residing at Westerville, in the county of Franklin and 5 State of Ohio, have invented a certain new and useful Improvement in Mining Apparatus, of which the following is a specification, reference being had therein to the accompanying drawings.

10 The invention relates to a mining apparatus of the class in which each is supported on a movable base (preferably a wheeled truck) and carries a horizontally projecting kerf cutting mechanism which 15 is capable of movement horizontally and is adapted to operate while supported on the base or truck. In using a mining apparatus of this type it is customary to lay a single track along the center of the room or entry 20 being cut. The mining mechanism or apparatus is then moved forward along this track to a point near the face and use is made of the cutting mechanism thereof to cut a kerf extending across the face from 25 one side of the room to the other. The cutting mechanism remains supported on the truck while the cutting is being carried on.

By my invention I have provided an apparatus in which the cutting mechanism is 30 movable not only transversely across the front of the machine (preferably angularly about a fixed vertical axis), but also translatively outward and inward away from and toward the central parts of the truck; 35 and I have provided power operated means for moving the cutting mechanism horizontally (in this case radially) relatively to the base frame to feed the mechanism to its work. The outer limit of radial movement 40 is controllable and can be varied for different angular positions. For this reason the machine can be used to cut kerfs having outlines other than semi-circular.

I have shown an apparatus which comprises a mining machine of the breast type supported on a turntable which is mounted on a wheeled truck; but it will be understood that there can be wide variation as concerns the specific form of cutting mechanism used and as concerns the means for

driving and controlling it. I have shown the mining machine as removable from the truck so as to be capable of operation at points separate from the truck; but it will be understood that the invention, in some respects, is not limited to an apparatus comprising a removable or separable complete mining machine. 55

In the apparatus shown the cutting mechanism is supported at a relatively high elevation, so as to cut a kerf a considerable distance above the mine floor. A relatively high kerf is preferable under many circumstances, but it will be understood that the invention is not limited as concerns the 60 height of the kerf.

The principal object of the invention is to provide a mining apparatus of the type specified having a cutting mechanism which is movable horizontally both angularly and 70 translatively, and which is preferably adapted for the cutting of kerfs non-circular in outline.

A further object of the invention is the provision of a mining apparatus comprising 75 a truck and a mining machine adapted to operate while supported on the truck, and also to be guided for movement off the truck for operation independently thereof.

Another object of the invention is the 80 provision of mining apparatus comprising a coal cutting machine and a supporting and transporting truck adapted to support the machine to cut in relatively elevated planes while the machine is upon the truck and also 85 to guide the machine for movement off the truck, either downward for operation upon the bottom proper of the mine, or at a higher elevation, as for operation upon a bench.

A further object is to provide an apparatus by means of which a series of cuts can be made radially from a center. A still further object is to provide a truck so constructed that a mining machine upon it can be readily turned end for end as desired. 95 Another object is to provide, in combination with a truck having means for reversing the position of the mining machine, mechanism whereby the mining machine motor can be connected with the truck wheels, when the 100

mining machine is in either position. Still other objects will be apparent from the following specification.

Of the accompanying drawings which illustrate one embodiment of my invention—

Figure 1 is a plan view showing the truck with the mining machine removed.

Fig. 2 is a side view of the truck with the mining machine removed.

Fig. 3 is a fragmentary sectional view taken along the line 3—3 of Fig. 1.

Fig. 4 is a plan view showing the mining machine upon the truck.

Fig. 5 is a rear view showing the mining machine upon the truck.

Fig. 6 is a diagrammatic view indicating one way in which an apparatus embodying my invention may be used.

Referring to the drawings, 1 represents as a whole the main base frame of the truck. This frame is preferably made up of rolled steel sections such as channels. The frame has side members 1^a, 1^a, and transverse end members 1^b, 1^b. The frame 1 is mounted by means of suitable bearings on transverse rotatable axles 2, 2, to which are secured track wheels 3, 3. At each end of each axle 2 there is a sprocket wheel 4. The uses of these sprocket wheels will be referred to herein after.

For purposes of illustration I have shown on the truck a breast mining machine of standard construction which need not be described in detail. The machine shown is similar to that described in the patent to E. R. Merrill, No. 798,108, dated August 28, 1905, and reference can be had to that patent for details not herein shown.

The mining machine comprises a carriage or cutter frame 27 and mounted upon this cutter frame is a cutting mechanism in the form of an endless cutter chain 28 carrying cutters 29. The connections between the cutter frame 27 and the main truck frame 1 are such that the cutter frame is movable horizontally either angularly or bodily outward and inward. When the cutter frame is a part of a standard breast mining machine such as is here shown, it is mounted on a bed frame 25 in such a way that it is longitudinally movable with respect thereto. The side parts of the bed frame constitute a guide which permits the cutter frame to have translative horizontal movements, but prevents relative angular movements.

In the construction shown, the bed frame 25 rests upon a supporting frame 5, which is rotatably mounted on the main truck frame 1 by means of a suitable turntable.

This turntable, as shown in the drawings, is movably supported on a ring 6 which is preferably angle-shaped in cross section with its horizontal flange extending outward from the top of its vertical flange. The ring is mounted between the side members 1^a, 1^a, of

the frame 1 and between two cross members 7, 7, which extend transversely between the side members. The vertical flange of the ring engages the vertical webs of the channel sections and the horizontal flange rests upon and is secured to the top flanges of the channel sections. The turn-table, in the construction illustrated, is in the form of a ring 8 which also is angle-shaped in cross section and constructed with its horizontal flange extending outward from the top of its vertical flange. The ring 8 is of such size that its vertical flange will lie just within the vertical flange of the ring 6 to be held thereby against lateral movement, rotary movement, however, being freely permitted. Interposed between the horizontal flange of the ring 8 and the horizontal flange of the ring 6 are a number of rollers 9, 9, which are held in place and guided by rings 10, 10.

It is upon the ring 8 that the frame 5 before referred to is mounted. This frame 5 comprises two bars 11, 11, which are preferably angle-shaped in cross-section with their vertical flanges extending upward at the outer sides. These bars 11, 11 are parallel throughout a part of their length; but at one end of the frame they diverge in order to be adapted for receiving the mining machine proper. The bars 11, 11 are connected at their ends by cross pieces 11^a and 11^b.

The bed frame 25 of the mining machine comprises the bottom shoes 25^a which characterize the machine of the Merrill patent above mentioned and which are adapted to slidably engage the angle bars 11 of the truck (as indicated in Fig. 5) as well as to rest upon and slide over the mine floor when the machine is used independently of the truck.

The turntable and the support therefor constitute a pivot device about which the cutter frame 27 is permitted to swing. This pivot device has a vertical axis, which in the construction shown is fixed with respect to the truck frame. It will be observed that this pivot device together with the aforesaid guide on the bed frame 27 serves at each position of transverse adjustment of the cutter frame to hold the said frame in a definite angular relation to the base frame. By this construction the cutter frame is held against indefinite movements relatively to the base frame, as the angular position is definitely fixed for each transversely adjusted position.

Near each end of the main truck frame 1 is a transverse bar or beam 12 which is preferably channel-shaped in cross section. The beams 12 are of such a height that they can engage the under surfaces of the bars 11, 11 of the frame 5 to give additional support to the frame. It is obvious that these beams

12, 12 prevent either end of the frame from swinging downward in case of uneven loading. Near one end of each of the bars 11 is a latch 13 which is so located that it can, 5 when the frame 5 is in central position, engage a suitable aperture 13^a in the top flange of one or the other of the beams 12, 12 to lock the frame 5 against rotary movement.

At one end of the frame 5, preferably at 10 the end at which the bars 11 diverge, there are secured two hinges 14, 14, for the attachment of jacks 15, 15. These jacks are adjustable in length by means of hand nuts 16, 16, and by being extended by means of 15 the nuts can be forced into engagement with the floor of the mine to lock the frame 5 against lateral movement in either direction.

Additional means for holding the machine to its work is provided in the form of jack 20 26 which is mounted on the bed frame of the mining machine. This jack can engage the roof or other wall of the mine and is inclined so as to effectively resist the reaction due to the engagement of the cutters with 25 the coal as they advance across the end of the cutter frame. As the jack 26 is attached to the bed frame of the mining machine it is adapted to perform the function described, both when the mining machine is 30 operated on the truck and when it is operated separately therefrom on the floor of the mine.

At the end of the frame 5 opposite to that at which the bars 11 diverge there is mounted 35 a transverse rotatable shaft 17 which carries at its inner end near the center of the frame a bevel gear wheel 18 and at its outer end a sprocket wheel 19 in longitudinal alignment with the sprocket wheels 4, 4 at 40 the corresponding ends of the axles 2, 2. 20 is a bevel gear wheel meshing with the bevel gear wheel 18. This wheel is secured to a suitable longitudinal shaft mounted in the bearing 21 on the frame 5. At the other 45 end of this shaft is a clutch element 22 adapted to be engaged by a similar clutch element on the mining machine to be described.

As the ends of the truck frame 1 are similar, and as the turntable is centrally located with respect to the axles, the frame 5 can be turned end for end on the truck whenever this is found necessary or convenient. As each end of each axle is provided with a 55 sprocket wheel 4 it is always possible to connect the sprocket wheel 19 on the shaft 17 with one or the other of the axles by means of a chain such as that indicated at 23. It will be understood that this chain 23 is used 60 only when it is desired to drive the truck from the mining machine motor in a manner to be described, and that it is removed when it is desired to turn the frame 5 on the main truck frame. Preferably a 65 second chain 24 is provided for connecting

the sprocket wheels 4, 4 at the side of the truck opposite to that on which the sprocket wheel 19 is located.

For driving the cutter chain 28 there is mounted upon the carriage or cutter frame 70 27 an electric motor 30 which is connected to the chain by means of suitable gearing 31. Mechanism is provided for automatically feeding the carriage or cutter frame backward and forward on the bed frame. This 75 mechanism comprises a transverse rotatable shaft which is provided at its end with pinions 32, 32 which mesh with racks 33, 33 secured to the bed frame. Mounted upon the transverse shaft are worms or spiral gear 80 wheels 34 and 35 with which mesh worms 36 and 37 on parallel longitudinal shafts. These parallel longitudinal shafts carry at their forward ends worm wheels 38 and 39 which mesh with a worm 40 on the vertical 85 driving shaft on the gearing 31. The wheels 34 and 35 are loosely mounted on the transverse feedshaft and either of them can be secured to it by means of the clutch 41. The clutch 41 is provided with an operating lever 90 42. By means of this lever either of the worm or spiral gear wheels 34 or 35 can be connected with the transverse feed shaft. When one wheel is connected the carriage or 95 cutter frame will be advanced relatively slowly and when the other wheel is connected the carriage or cutter frame will be retracted relatively rapidly.

The longitudinal shaft which carries the worm or spiral gear 36 also carries a clutch 100 element 43 which is adapted to engage the clutch element 22 on the truck when the machine is in the proper position. It will be obvious that when the clutch elements are engaged, power can be transmitted from 105 the motor to the mining machine through the shafts and gearing which have been described to drive the wheels of the truck.

The mining machine can be locked in place on the frame 5 by means of the devices indicated in 47, 47.

When the invention is embodied in an apparatus of the form shown in the drawings I prefer to follow the method of operation which is indicated in Fig. 6.

A track 44 is laid down the center of the room and the machine is run into the room by its own power. When the machine has reached the proper place the wheels are blocked preferably by means of the device 115 120 indicated in Fig. 2 which comprises two blocks 45, 45 adapted to engage the wheels. Between these blocks 45, 45 is an adjustable strut 46 by means of which the blocks can be forced apart and into firm engagement 125 with the wheels and the track. The chain 23 is then removed and the frame 5 unlocked from the main truck frame 1. The frame 5 with the mining machine is then swung to one side, and the machine is jacked in posi- 130

tion in the usual way, use being also made of the jacks, 15, 15 and 26 which engage the mine floor and roof, respectively, to prevent the frame 5 from swinging. The mining 5 machine is then started and a horizontal laterally extending kerf is cut into the coal. After the kerf is cut the cutter or carriage frame is retracted, the jacks are loosened and the machine is swung into position for 10 another cut. The machine is secured in this second position and the mining machine is then started, a second cut into the coal being made. In Fig. 6 the full lines show the machine completing one cut, and the dotted 15 lines show it completing another cut. This operation is repeated, the machine being swung on the turntable, until a complete kerf semi-circular in outline has been cut into the coal. Then the machine is removed from 20 the room by its own power and the coal is broken down in the usual way. It will be noted that by the use of this apparatus, the room has a semi-cylindrical face instead of a plane face. This, however, is not a disad- 25 vantage but, on the contrary, is a distinct advantage, as loading of the coal is made easier.

It will be understood that the apparatus can be used in ways differing from the way 30 above described and it is not limited to the cutting of a complete semi-circular series of radial cuts. As the cutting mechanism is movable radially away from and toward the central parts of the truck, and as the outer 35 limit of cutting is readily controllable for each angular position by means of the lever 42 the radial distances from the central part of the truck to the outer edge of the kerf at different points, circumferentially separated, 40 can be varied as may be desired to cut a kerf having an outline other than a simple semi-circular outline, such as that indicated in Fig. 6. In this respect an apparatus embodying my invention, has marked advan- 45 tage over earlier mechanism which were adapted only for cutting arcuate kerfs.

By means of an apparatus embodying my invention a distinct saving of time and labor is effected. I am enabled not only to 50 save the time ordinarily required for unloading the machine from the truck and re-loading it, but also to save a large part of the time usually consumed in moving the machine from one position to another. By 55 means of the turntable mounting, the machine after the jacks have been loosened can be very easily and quickly moved and rapidly placed in exactly the desired position. The time between cuts is in this way 60 very materially reduced. If at any time it is desired to use the mining machine in the usual way apart from the truck, the machine can be easily removed after removing the locking devices 47, 47. In removing the 65 mining machine its shoe bars 25^a slide, as

stated above, upon the guide rails 11 of the truck and, when the machine is off the truck, said shoe bars slidably support it for operation on the mine floor. It will be seen that the guide rails 11 of the truck, constituting 70 as they do a part of the rotatable supporting frame, are adapted to discharge the machine in any desired angular direction, or when loading to receive it from any desired angular direction; and by reason of the elevated position of the supporting frame of the truck it is especially adapted to discharge the mining machine in various angular directions upon a bench. 75

I have already noted that my invention in 80 some respects is not limited to the type of mining machine employed, and it may be observed in that connection that the manner of handling the apparatus, whether the machine is operating while on the truck or 85 separate therefrom, will depend in some measure upon the type of mining machine employed.

I do not herein claim as a part of my present invention the mining machine truck 90 alone, as that is made the subject of my co-pending application for mining machine trucks, Serial No. 871,712, filed November 12, 1914, as a division of this application. 95

What I claim is:

1. In a mining apparatus, the combination of a main base frame, a supporting frame having longitudinally extending guide bars mounted on the base frame for movement about a vertical axis, and a mining machine mounted on the supporting frame and comprising a bed frame, slidably engaging the said guide bars, a horizontally projecting constantly moving continuously acting kerf cutting mechanism on the bed 100 frame operable while the machine is on the supporting frame and a motor for driving the cutting mechanism, the said mining machine being readily separable from the base frame and the supporting frame and oper- 110 able independently thereof.

2. In a mining apparatus, the combination of a main base frame, a supporting frame having longitudinally extending guide bars mounted on the base frame for movement about a vertical axis, and a mining machine mounted on the supporting frame and comprising a bed frame slidably engaging the said guide bars, a horizontally projecting cutting mechanism mounted on 120 the bed frame for reciprocatory movement radially with respect to the said axis and active at points widely separated transversely of the direction of reciprocation and a motor for driving the cutting mechanism, the said mining machine being operable while on the said supporting frame and being also readily detachable therefrom and operable independently thereof.

3. In a mining apparatus, the combina- 130

- tion of a wheeled truck, a supporting frame having longitudinally extending guide bars mounted on the frame of the truck for movement about a vertical axis, and a mining machine mounted on the supporting frame and comprising a bed frame slidably engaging the said guide bars, a horizontally projecting constantly moving continuously acting kerf cutting mechanism operable
- 5 10 15 20 25 30 35 40 45 50 55 60 65
- while the machine is on the supporting frame and a motor for driving the cutting mechanism, the said mining machine being readily separable from the truck and operable independently thereof.
4. In a mining apparatus, the combination of a wheeled truck, a supporting frame rotatably mounted on the truck, a mining machine separably mounted upon the supporting frame and provided with a clutch element connected to its motor, a clutch element on the supporting frame adapted to be engaged by the clutch element on the mining machine, and power transmitting devices adapted to connect the said clutch element on the turntable with the truck wheels.
5. In a mining apparatus, the combination with a truck comprising a frame, two axles, and track wheels on the axles, of a supporting frame rotatably mounted on the truck frame midway between the axles, of a mining machine separably mounted on the supporting frame and provided with a clutch element connected to its motor, a clutch element on the supporting frame adapted to be engaged by the clutch element on the mining machine, a sprocket wheel on the supporting frame connecting with the last said clutch element, a sprocket wheel on one axle adapted to aline with the sprocket wheel on the supporting frame when the frame is in one position, a sprocket wheel on the other axle adapted to aline with the sprocket wheel on the supporting frame when the frame is in another position, and a chain for connecting the sprocket wheel on the supporting frame with whichever axle sprocket wheel it may be in alinement with.
6. In a mining apparatus, the combination of a wheeled truck, a supporting frame rotatably mounted on the truck, a mining machine separably mounted upon the supporting frame and provided with a clutch element connected to its motor, a clutch element carried by the truck and adapted to be engaged by the clutch element of the mining machine, and power transmitting devices for connecting the clutch element on the truck with the truck wheels.
7. In a mining apparatus, the combination of a truck having a frame and supporting wheels, a supporting frame rotatably mounted on the truck frame, a mining machine separably mounted upon the supporting frame to turn therewith, said mining
- machine having a cutting apparatus arranged to project from the truck to engage the coal, a clutch element carried by the mining machine and connected to its motor, a clutch element carried by the truck and adapted to be engaged by the first named clutch element, and power transmitting devices between the clutch element of the truck and the truck wheels.
8. In a mining apparatus, the combination with a truck comprising a frame, two axles, and track wheels on the axles, of a supporting frame rotatably mounted on the truck frame midway between the axles, a cutter mechanism mounted on the supporting frame, a motor for driving the cutter mechanism, a sprocket wheel on the supporting frame connected with the motor, a sprocket wheel on one axle adapted to aline with the sprocket wheel on the supporting frame when the frame is in one position, a sprocket wheel on the other axle adapted to aline with the sprocket wheel on the supporting frame when the frame is in another position, and a chain for connecting the sprocket wheel on the supporting frame with whichever axle sprocket wheel it may be in alinement with.
9. In a mining apparatus, the combination with a truck comprising a frame, two axles, and track wheels on the axles, of a supporting frame rotatably mounted on the truck frame midway between the axles, a cutter mechanism mounted on the supporting frame, a motor for driving the cutter mechanism, a sprocket wheel on the supporting frame connected with the motor, a sprocket wheel on one axle adapted to aline with the sprocket wheel on the supporting frame when the supporting frame is in one position, a sprocket wheel on the other axle adapted to aline with the sprocket wheel on the supporting frame when the frame is in another position, a chain for connecting the sprocket wheel on the supporting frame with whichever axle sprocket wheel it may be in alinement, and means for connecting together the two axles for the transmission of power from one to the other.
10. In a mining apparatus, the combination with a truck comprising a frame, two axles, two track wheels on each axle, and two sprocket wheels on each axle respectively adjacent the track wheels, of a supporting frame rotatably mounted on the truck frame midway between the axles, a cutter mechanism mounted on the turntable frame, a motor for driving the cutter mechanism, a sprocket wheel on the supporting frame connected with the motor and arranged to aline with a sprocket wheel on one axle when the frame is in one position and to aline with a sprocket wheel on the other axle when the frame is in another position, a chain for connecting the sprocket

wheel on the supporting frame with whichever axle sprocket wheel it may be in alinement, and a chain for connecting the two axle sprocket wheels at the side of the truck 5 opposite to that on which the sprocket wheel on the supporting frame is located.

11. In a mining apparatus, the combination of a movable main base frame, supporting track wheels therefor, a supporting 10 frame on the base frame movable about a vertical axis, an elongated horizontally projecting cutter frame carried by the supporting frame and movable with respect thereto longitudinally outward and inward, a kerf 15 cutting mechanism carried by the cutter frame and comprising devices constantly moving relatively thereto, a motor carried by the supporting frame for driving the cutting mechanism, and means for transmitting the power of the motor to the track 20 wheels when the supporting frame is in one of several horizontally differing positions.

12. In a mining apparatus, the combination of a movable main base frame, supporting track wheels therefor, a supporting 25 frame on the base frame movable about a vertical axis, an elongated horizontally projecting cutter frame carried by the supporting frame and movable with respect thereto longitudinally outward and inward, a kerf 30 cutting mechanism carried by the cutter frame and comprising devices constantly moving relatively thereto, a motor carried by the supporting frame for driving the cutting mechanism, and means for transmitting the power of the motor to the track 35 wheels when the supporting frame is in either of two diametrically opposite positions.

13. In a mining apparatus, the combination of a wheeled truck, a supporting frame rotatably mounted on the truck, a mining machine separably mounted upon the supporting frame and provided with a clutch 40 element connected to its motor, a clutch element on the supporting frame adapted to be engaged by the clutch element on the mining machine, and means for transmitting the power of the motor from the clutch element 45 on the supporting frame to the track wheels 50 when the supporting frame is in either of two diametrically opposite positions.

14. In a mining apparatus, the combination of a wheeled truck, a supporting frame 55 rotatably mounted on the truck, a mining machine separably mounted upon the supporting frame and provided with a clutch element connected to its motor, a clutch element on the supporting frame adapted to be engaged by 60 the clutch element on the mining machine, a sprocket wheel on the supporting frame connected with the clutch element thereon, a sprocket wheel on one axle adapted to aline 65 with the sprocket wheel on the supporting frame when the supporting frame is in one

position, a sprocket wheel on the other axle adapted to aline with the sprocket wheel on the supporting frame when the frame is in another position, a chain for connecting the sprocket wheel on the supporting frame 70 with whichever axle sprocket wheel it may be in alinement, and means for connecting together the two axles for the transmission of power from one to the other.

15. In a mining apparatus, the combination of a wheeled truck, comprising a frame, two axles and track wheels on the axles, a supporting frame rotatably mounted on the truck, a mining machine separably mounted upon the supporting frame and provided 75 with a clutch element connected to its motor, a clutch element on the supporting frame connected with the clutch element on the mining machine and arranged to aline with a sprocket wheel on one axle when the frame 80 is in one position and to aline with a sprocket wheel on the other axle when the frame is in another position, a chain for connecting the sprocket wheel on the supporting frame with whichever axle sprocket 85 wheel it may be in alinement, and a chain for connecting the two axle sprocket wheels at the side of the truck opposite to that on which the sprocket wheel on the supporting frame is located. 90

16. A coal mining apparatus having, in combination, a transporting wheeled truck having two pairs of wheels adapted to be fitted to and braced by the rails of a mine track, a supporting frame mounted to swing laterally on and be wholly supported by the truck, coal cutting mechanism mounted on the supporting frame, the said mechanism comprising a cutter frame mounted in fixed angular relation to the supporting frame 105 and a horizontally traveling cutter chain carried by said cutter frame, the cutter frame and chain being mounted to project toward the coal beyond all other parts of the apparatus and the said supporting frame and the cutting mechanism being horizontally movable together while the truck remains stationary, and means adapted to engage positively with the wall of the mine room to hold the cutter frame against horizontal lateral movement due to the reaction of the coal on the cutter chain. 110

17. A coal mining apparatus having, in combination, a transporting wheeled truck having two pairs of wheels adapted to be 120 fitted to and braced by the rails of a mine track, a supporting frame mounted to swing laterally on and be wholly supported by the truck, a coal cutting machine mounted on the supporting frame, the said machine 125 comprising a bed frame in fixed angular relation to the supporting frame, a reciprocating cutter frame mounted on the bed frame in fixed angular relation thereto and a horizontally traveling cutter chain on the 130

cutter frame, the cutter frame and chain being mounted to project toward the coal beyond all other parts of the apparatus and the said supporting frame and the cutting mechanism being movable together while the truck remains stationary, and means adapted to engage positively with the wall of the mine room to hold the cutter frame against horizontal lateral movement due to the re-
10 action of the coal on the cutter chain.

18. In a mining apparatus, the combination of a base frame, track wheels supporting said frame, an elongated supporting frame mounted to turn on an upright axis relatively to the base frame and having a horizontally widely extending bearing support on the base frame, cutting mechanism mounted to move longitudinally of the supporting frame toward the coal to points in advance of all other parts of the apparatus and means for positively engaging the ground at points radially outside of the aforesaid bearing support for the supporting frame to additionally support said frame and hold it against lateral movement.
20

19. Coal cutting apparatus comprising, in combination, a base, a rotatably movable support mounted on said base, a complete coal cutter comprising a shoe on which said cutter is adapted to slide on the mine floor independently of the base, a cutter chain, feeding mechanism, and an actuator for said

cutter chain and said feeding mechanism, said coal cutter being separably mounted on said support and detachable therefrom for operation independent of said base.
35

20. Coal cutting apparatus comprising, in combination, a complete mining machine having cutting apparatus adapted to form an undercut in coal, a wheeled truck, a horizontally rotatable frame on the truck having guideways formed of longitudinally arranged horizontally and vertically disposed guide bars, said mining machine comprising a shoe element at its bottom related to and adapted to slide along said guideways while supported thereon and also to slide upon the mine floor when the mining machine is used independently of the base for under-
40 cutting.
45

21. In a mining machine truck, truck wheels, a lower frame carried thereon, a machine guiding frame swiveled on said lower frame, a mining machine supported by said wheels and movable longitudinally of said guiding frame, and means for driving said wheels from said machine in one position of the latter.
50

In testimony whereof I affix my signature in presence of two witnesses.
